US0D1083140S

(12) **United States Design Patent** (10) **Patent No.:** **US D1,083,140 S**
(45) **Date of Patent:** **** Jul. 8, 2025**

(54) **BOOSTER PLATE**

(71) Applicant: **Agilent Technologies, Inc.**, Santa Clara, CA (US)

(72) Inventors: **Jason Dell'Arciprete**, Santa Clara, SC (US); **Jon Arsenault**, Santa Clara, CA (US)

(73) Assignee: **Agilent Technologies, Inc.**, Santa Clara, CA (US)

(**) Term: **15 Years**

(21) Appl. No.: **29/928,117**

(22) Filed: **Feb. 8, 2024**

Related U.S. Application Data

(62) Division of application No. 29/819,237, filed on Dec. 14, 2021, now Pat. No. Des. 1,021,136.
